F. PORSCHE

SWITCHING MECHANISM IN CONNECTION WITH MOTOR CARS

Filed Jan. 28, 1925

UNITED STATES PATENT OFFICE.

FERDINAND PORSCHE, OF STUTTGART-UNTERTURKHEIM, GERMANY, ASSIGNOR TO
DAIMLER-MOTOREN-GESELLSCHAFT, OF STUTTGART-UNTERTURKHEIM, GERMANY,
A CORPORATION OF GERMANY.

SWITCHING MECHANISM IN CONNECTION WITH MOTOR CARS.

Application filed January 28, 1925. Serial No. 5,351.

To all whom it may concern:

Be it known that I, FERDINAND PORSCHE, a citizen of the Republic of Czechoslovakia, residing at Stuttgart-Unterturkheim, Wurttemberg, Germany, have invented certain new and useful Improvements in a Switching Mechanism in Connection with Motor Cars, of which the following is a specification.

10 The object of my invention relates to a switching mechanism for actuating electric sound producers and for the blinding of searchlights of motor cars and more especially of that kind of switching mechanism, which is operated by means of a ring-switch arranged on the hand steering wheel.

The feature of my invention consists therein, that I employ said ring-switch for operating the contact both, of the sound producer and of the blinding device and that the closing of the one of said contacts is being effected by the pressing down of said ring-switch, whilst the other one is closed by lifting of same.

25 It is another feature of my invention that the contact-brackets may also serve as brackets or supports of the ring-switch.

The advantages derived therefrom consist in the following:

30 The devices or means required are disposed and constructed in such way that the motorist is permitted to concentrate his entire attention to his main task, viz: to the steering of the motor car, and that he is relieved from paying additional attention to the operation of the accessory devices above mentioned.

The accompanying drawing shows one form of execution of my said invention in 40 which

Fig. 1 represents the new arrangement in its totality and schematically,

Fig. 2 a top view of the hand wheel and

45 Fig. 3 a section through the hand steering wheel.

a designates the hand steering wheel on which the ring-switch *b* is arranged and by means of which both, the electric sound producer 2 and the blinding device of the 50 search light are operated.

For realizing the one aim of the invention viz: the operating of the sound pro-

ducer, the ring *b* is pressed down closing thereby the contact *b*₁—*c*. The current is then flowing from the battery through the 55 sound producer, the resistance 4, the throw-over-switch 6, line 7, the one guide-pin *f* to the contact-ring *c* and from here through the switch-ring *b*, which is in electric connection with the mass of the motor car, 60 back to the battery.

Parallel to the resistance 4 there is disposed a second conducting line 1.

For the purpose of producing great distance sounds and in order to avoid thereby 65 a weakening of the current by the resistance 4, the switch 6 is thrown over so that when the contact *b*₁—*c* is closed the line 1 is being connected by means of the line 7 and the pin *f* with the contact-ring *c*.

70 For attaining the second object of this invention viz: to blind the search lights, the ring-switch is lifted and the contact *b*₂—*d* is closed.

The current is then flowing from the battery through the electromagnet of the switch 5, and through the line 3 to a sleeve *i* which sleeve is surrounding the insulated bolt or pin *f*, said sleeve *i* being in electric connection with the contact *d*.

75 When the circuit is closed the current is flowing through the contacts *b*₂—*d* through the mass of the motor car back to the battery.

80 As appears from Fig. 2 the contacts *b*₁—*c* and *b*₂—*d* are disposed in the hollow space of the ring-switch *b*. The ring-switch is supported by springs *gh*. These springs by means of the contact-ring *c* are pressed between the insulating rings *k*, said insulating 85 rings being pressed against the contact-ring *d*. The contact-ring *c* above referred to is screwed to the bolt *f*.

90 The purpose of providing said springs *gh* consists therein to keep the ring-switch in inoperative position when the same is neither lifted nor pressed down (see Fig. 2); whilst the effect realized by the ring-switch *b*₁—*c* resides in the fact that the contacts of the sound producer and those *b*₂—*d* serving for the blinding of the search-light immediately 95 close their circuits if said ring-switch at any point of its circumference is pushed down or lifted.

The ring-switch may however just as well be pushed down at one side and lifted at another side, whereby it is attained that sound signals are emanated and that the blinding is at the same time introduced.

According to the invention the operation both of the sound producer and the blinding of the search-light is considerably simplified by the fact that the motorist need not 10 remove his hand from the steering wheel; he only needs to concentrate his attention to the steering of his motor car.

I claim:

1. In a circuit closer, a vertically disposed 15 insulated conductor member mounted in a steering wheel, the upper end of said member constituting one contact, a contact ring surrounding said member and insulated therefrom, a hollow annular member slid- 20 able on said insulated member and insulated therefrom and from said contact, and having a contact cooperating with the upper end of said insulated member to complete one circuit and having a contact spaced

from the first named contact and adapted 25 to contact with said ring.

2. In a circuit closer, a vertically disposed insulated conductor member mounted in a steering wheel, the upper end of said member constituting one contact, a contact 30 ring surrounding said member and insulated therefrom, a hollow annular member slid-able on said insulated member and insulated therefrom and from said contact, and hav- 35 ing a contact cooperating with the upper end of said insulated member to complete one circuit and having a contact spaced from the first named contact and adapted to contact with said ring, and springs within said annular member for holding the contact in inoperative position.

In testimony whereof I affix my signature in presence of two witnesses.

FERDINAND PORSCHE.

Witnesses:

JORDAN BAUER,
ERIK W. MAGNUSON.
